(57) **CLAIM**

The ornamental design for a structural post, as shown and described.

DESCRIPTION

FIG. 1 is a front view of a structural post as showing our new design;

FIG. 2 is a rear elevational view thereof;

FIG. 3 is a right side elevational view thereof;

FIG. 4 is a left side elevational view thereof;

FIG. 5 is a top plan view thereof;

FIG. 6 is a bottom view thereof;

FIG. 7 is a cross-sectional view of the structural post shown in FIG. 1 taken along line 7-7;

FIG. 8 is a cross-sectional view of the structural post shown in FIG. 5 taken along line 8-8;

FIG. 9 is a cross-sectional view of the structural post shown in FIG. 5 taken along line 9-9;

FIG. 10 is a perspective view thereof; and,

FIG. 11 is a perspective view showing the structural post in an environment of use, wherein the structural post is connected to a structural members via metal fittings. Both the structural members and metal fittings shown in broken lines illustrate environmental subject matter and form no part of the claimed design.

The present design repeats only in the upward/downward direction of the front view. The broken lines in the drawings show environmental subject matter only and form no part of the claimed design.
